TOM M. OWEN, OF WALLACE, AND MICHAEL P. DALTON, OF MULLAN, IDAHO.

FLOTATION APPARATUS.

Application filed May 29, 1925. Serial No. 33,601.

Our invention is an improved apparatus for the flotation concentration of ores, but has utility for other processes wherein it is necessary to agitate or aerate, or both 5 agitate and aerate a body of liquid or of mixed liquid and solids. In the practice of the flotation process by the mechanical agitation method, it is generally, in fact almost invariably, desirable to subject the ore pulp 10 to agitation in a considerable number of separate agitation cells. This involves the necessity of providing some means of conveying the pulp from cell to cell and maintaining it at the proper level in each cell. 15 Where the conformation of the land admits it is often convenient to effect this purpose by placing the cells successively at a lower level and initially supplying the pulp to the uppermost cell. It frequently happens, however, that it is necessary or advantageous to 20 build all of the cells upon the same level.

In a prior application filed by us (Serial No. 724,250, filed July 5, 1924), we disclosed a flotation apparatus of the type in which 25 the cells were erected on the same level, with the agitator rotors mounted on a single shaft extending throughout a series of cells. Bearings were provided at intervals along the shaft, preferably between the cells and 30 within bearing spaces from which the pulp is excluded. Associated with each of the cells (except the first in the series) was disclosed an elevator chamber, in which was a rotary elevator mounted on the same shaft 35 as the agitator rotors. These elevator chambers were connected with the cells on either side in such a way that the pulp flowed from one cell into the chamber at a low level, and thence lifted to a high level 40 so as to impart the necessary flow by gravity into the next cell. In this way the pulp flow was maintained throughout the series of cells on the same level.

The present invention involves the same 45 principle of operation, but differs in its application, in that the elevator chambers are eliminated and one end portion of each agitator rotor utilized as the elevator, this being readily accomplished by making certain 50 changes in the structure of the cells. The results are quite the same, but with the advantage that the cells are of a simpler construction, shorter in length and less costly to install and maintain.

55 The features embodying the invention will

now be described in connection with the accompanying drawings in which

Figure 1 is a plan view, with certain details omitted, of three flotation cells embodying my invention;

Figure 2 is a plan view upon an enlarged scale of one of the cells shown in Figure 1;

Figure 3 is a transverse sectional view upon the line 3—3 of Figure 2;

Figure 4 is a longitudinal sectional view 65 upon the line 4—4 of Figure 2;

Figure 5 is a transverse section taken on line 5—5 of Figure 2; and

Figure 6 is a detail view in longitudinal section on line 6—6 of Figure 5.

As illustrated in Figure 1, the pulp is initially delivered by any suitable means to the cell 1, shown at the right, this being the head of the machine. As shown herein the three cells 1, 2, and 3 are similar except in 75 the fact that cell 1 is not provided with any elevator mechanism, the pulp being initially delivered to that cell from some outside source. In the form shown each cell is divided into two compartments by means 80 of a central partition 4. In practice, the number of partitions may vary or be entirely dispensed with, but in most instances one or more such partitions are advantageous in order to get better control of the differing 85 grades of concentrates.

Within each cell is a cylindric agitator rotor 5, mounted on a main shaft 6, extending lengthwise through the cells, and journaled in bearings at 7 and 8, located at the 90 head end of the machine; at 9 and 10, between the cells 1 and 2, and 2 and 3 respectively; and at 11, the tail end of the machine. This shaft may be operated from any suitable source of power as through a 95 belt applied to the pulley 12.

Each cell is of substantially rectangular form and comprises a vertical back wall 13, and vertical end walls 14 and 15. As indicated in Figure 5, the front wall 16, opposite the agitator rotor extends upwardly to a point somewhat below the level of the axis of the shaft and there carries an inclined apron 17 provided at its upper edge with a vertical lip 18 over which the concentrate froth flows into the launder 19. The height of front wall 16, the presence, or absence, and the size of members 17 and 18 are preferably controllable at will to suit the requirements of the pulp under treat- 110

ment. The space immediately below the members 17 and 18 and forwardly of the agitator chamber form what is termed spitz-box K, having a constricted opening, the size depending on the length of member 17.

An agitator rotor is mounted in each cell, such rotor being shown in transverse section in Figure 3, and consisting of a pair of spaced pulleys 20, 20, or the like upon the rims of which are affixed a series of longitudinal strips 21, spaced apart circumferentially to form intervening slots 22.

Extending over the entire top of each cell (see Fig. 5) is a hood 23, at the front of which is a depending vertical wall 24, which terminates below the level of the shaft 6, and of the overflow lip 18. A vertical baffle 25 has its upper edge extended between the depending wall 24 and the periphery of the agitator rotor. The agitator rotor revolves in a counter-clockwise direction as indicated by the arrows, and throws the pulp upward and forward as indicated by the arrows 30, and at the front of the cell the pulp passes through the slot 26 between the walls 24 and 25 into the spitz-box K as indicated by the arrow at that point. The lower edge of the baffle 25 is spaced above the floor of the cell to form an opening or slot 27. An inclined floor 28 preferably extends from the front wall 16 to the horizontal floor of the cell to assist in directing the flow of pulp through the slot 27 in the direction indicated by the arrow placed at that point.

The baffle 24 in connection with the front wall 16 and floor board 28, forms a spitz-box at the front of the cell, the overflow of froth over the lip 18 being received in the launder 19 and discharged through the duct 29.

It will be noted that in the preceding description no mention is made of an elevator chamber or an elevator. In fact, no such parts exist as separate elements of the apparatus, but their function is performed by a section of each agitator rotor, at the head end of each cell, and by the adjacent portion of the cell. Thus, as shown in Figures 2 and 4, the portion at the right end of the cell is the elevator section thereof. Immediately in front of the end of the rotor is an inlet chamber 30, between the end wall 14 and head end of the spitz-box K, being separated therefrom by a transverse partition wall 31 (Figure 4). The rear wall of the chamber 30 is formed by the same vertical walls 24 and 25, extending throughout the full length of the cell, although the slot between their overlapping edges is closed by a block 32, inclined downwardly from the end wall 14 beyond the partition wall 31, and projecting into the slot 26 to the spitz-box K to the left. The purpose of this block 32 will be presently pointed out. The front of the chamber 30 is formed by a ver-

tical wall 33, extending from the transverse partition wall 31, in contact with the end of the end wall 14 of the associated cell, and thence beyond to the end wall 15 of the adjacent or preceding cell. Rearwardly of the front wall 33 is a vertical wall 34, extending crosswise between the end walls 14 and 15 and forming an intermediate chamber 35, between the preceding cell and the inlet chamber 30, said intermediate chamber 75 being just forward of the shaft bearing 9 and the space between the cells occupied thereby. As clearly shown in Figure 4, the inlet chamber 30 is about one half the height of the cell and is closed by a removable lid 80 36, having one central opening 36. Moreover, the inlet chamber communicates at its bottom with the cell proper, or agitator compartment, by an opening or slot 37, the same being a continuation of the slot 27 on the 85 other side of the partition wall 31.

As clearly shown in Figure 4, an opening 38 is formed in the tail end wall 15 of the preceding cell, and near the bottom thereof, said opening or passage communicating with the intermediate chamber 35. In the opposite wall 14, the same being the head end wall of the cell to which the pulp is flowing, is an opening 39 from the intermediate chamber 35 into the inlet chamber. This 95 opening 39, is located at a higher level than the inlet opening 38 to the chamber 35, its lower edge determining the pulp level in the preceding cell. In other words, wall 40, below the opening 39, acts as a weir over which 100 the pulp flows into the inlet chamber 30. For this reason the wall 40 is preferably made in sectional form, as shown, so that the level may be altered in order to change the pulp level in the preceding cell, as required.

The same arrangement is duplicated in the next cell beyond, and regardless of the number of cells in the series, all between the head and tail cells are of the same construction.

Assuming then that the pulp is introduced into the cell 1 at the head of the series, it is agitated therein by the rotation of the agitator rotor, and what mineral laden froth is formed overflows the spitz-box into the launder 19. The pulp on reaching the tail end of the spitz-box of head cell 1, passes through the opening 38 into the intermediate chamber 35, the level 120 of pulp therein, as well as the cell 1, being governed by the height of the weir 40, as already described. As the pulp overflows the weir into the inlet chamber 30, it passes through the opening 37 into the bottom of 125 the agitator compartment of cell 2, where it is picked up by the end portion of the rotor and carried upwardly around the same in a path indicated by the arrows in Figure 3, the general movement of the pulp 130

being tangential to the periphery of the rotor. There being no definite line of division between the portion of the rotor serving as the elevator and the remaining portion acting as the agitating element, it is possible to assume that the portion directly opposite the chamber 30 is the elevator—this portion being indicated by the bracket 41 in Figure 4. Manifestly there will be some commingling of the entering pulp and the pulp already in the cell and undergoing treatment, but, since the general movement of the pulp body is from head to tail, there is little or no retardation of the incoming pulp. In other words, it is not necessary that a distinct elevator chamber be formed, providing the pulp is not thrown back into the inlet chamber, which, of course would cause recirculation and retard the action. This, however, is avoided by closing off the inlet chamber 30 at the top, by the block 32, which deflects the pulp laterally into the mass of the pulp, beyond the zone of the entering pulp.

If desired, the longitudinal strips 21 may stop at the end elevator section and a different type of elevating elements be substituted, although this is a matter of choice since the strips 21 will serve equally well to pick up the pulp and carry it upwardly and discharge it at a higher level than that at which it entered, which is equivalent to saying that it discharges the pulp at a higher level than the pulp level in the preceding cell.

As is customary in apparatus of this type, air is admitted to the cells, preferably through an opening in one of the end walls, surrounding the rotor shaft. The air thus admitted or drawn into the cell is mixed with the pulp in the agitating process within the cell. The pulp thus undergoing treatment is being continually discharged into the spitz-box K, through the space or slot 26, the froth rising to the top where it overflows into the launder 19, whereas the heavier mass is returned to the agitator compartment through the opening 27, at the bottom of the spitz-box.

In the practical operation of flotation apparatus, it has been found that where an excess of air is admitted to the cells, large bubbles are formed in the pulp froth which rise to the top of the spitz-box and give way, thus creating a more or less disturbed condition in the froth layer. In order to eliminate this condition and to maintain a froth of a fine bubble texture and thus to promote a condition of quiescence in the froth layer, we have devised a simple and effective expedient for bringing about this result.

Referring to Figures 5 and 6, we mount a vertical plate 42 to the outer face of the upper section 24 of the front wall of the

cell, with a space of $\frac{1}{8}$ to $\frac{1}{2}$ inch between. The lower edge of the plate extends below the bottom edge of the wall, a distance of from 1 to 2 inches, so that the froth passes underneath the lower edge of the plate before passing upwardly into the froth layer at the top of the spitz-box. The plate 42 is spaced from the wall 24 by suitable strips 43 of wood arranged vertically spaced apart at intervals. As the froth enters the spitz-box through the opening 26, the large bubbles rise to the top and are trapped behind the lower edge of the plate 42, whereas the small and uniformly fine bubbles pass beneath the plate and enter the froth layer at the top of the spitz-box. The larger bubbles thus trapped by the plate are forced upwardly in the vertical passage formed by the plate 42, and as they break the air is released and escapes from the top to the atmosphere. It is preferred, however, to provide a chamber 44 along the top of the plate 42 with a pipe 45 connected with one end thereof, its other end communicating with the interior of the cell, through an intake inlet opening, preferably associated with the air inlet openings to the cell located around the shaft 6, at the point where it passes through the side wall of the cell. Thus the air entering the chamber 44 from below is returned to the cell, the reason being that the air is usually charged with a certain amount of the pulp treating reagents and thus by using the air over again, these reagents are recovered and utilized.

We claim as our invention:

1. A flotation apparatus comprising a series of cells, an agitator rotor extending horizontally of each cell, an inlet chamber communicating with each cell adjacent the bottom thereof through a discharge opening directed toward a relatively short longitudinal portion of said rotor and connected with the preceding cell through an inlet opening at a substantially higher level than said discharge opening, said portion of the rotor acting to elevate the pulp to a predetermined level in each cell.

2. A flotation apparatus comprising a series of cells, an agitator rotor extending lengthwise of each cell, intermediate chambers connecting the tail end of each cell with the head end of the following cell, through a discharge slot adjacent the bottom thereof and directed toward a longitudinal portion of said rotor less than the full length thereof, said portion of each agitator rotor acting to elevate the incoming pulp to a predetermined level in each cell above the discharge opening thereto.

3. A flotation apparatus comprising an aligned series of cells, an agitator rotor in each cell, a duct connecting the head end of each cell with each preceding cell, below the pulp level in said preceding cell through a

slot directed toward a relatively short longitudinal portion adjacent the end of each rotor, said longitudinal portions of said rotors acting to elevate the pulp to a level in each cell above the level at which it is discharged from the preceding cell.

4. A flotation apparatus comprising a series of cells, a rotary agitator extending longitudinally the length of each cell, a chamber connecting each cell with the preceding cell through an inlet slot adjacent the bottom of said cell and below the level of the discharge from said preceding cell, said slot being directed toward a section of said rotor at the head end of said cell, whereby said end section acts to elevate the pulp entering said cell and to maintain a predetermined pulp level therein.

5. A flotation apparatus comprising a cell, a rotary agitator extending lengthwise of said cell, an inlet chamber communicating with said cell through a longitudinally extending opening below the pulp level in said cell and directed toward a relatively short end of said agitator at the head end of said cell, and a spitz-box extending throughout the remaining portion of the length of said agitator, said end portion thereof acting to elevate the pulp entering said cell through said opening to the normal pulp level therein.

6. A flotation apparatus comprising a cell, a rotary agitator extending lengthwise of said cell, a spitz-box communicating with said cell and extending substantially throughout the length thereof, an inlet chamber formed at one end of said spitz-box and

communicating with said cell through an outlet opening adjacent the bottom thereof and opposite a longitudinal end portion of said agitator, said inlet chamber having an inlet opening above said outlet opening, said end portion of the agitator forming an elevator and the remaining portion forming the agitating and discharging section thereof.

7. A flotation apparatus comprising an agitator chamber, a spitz-box separated from said agitator chamber by vertical partition walls forming a passage connecting said chamber with said spitz-box below the froth level therein, a wall spaced outwardly from said partition wall and extending into said spitz-box below the froth level therein and terminating substantially opposite the passage from said agitator chamber and said spitz-box, to form a vertical passage for the escape of air for the purpose described.

8. A flotation apparatus comprising an agitator chamber, a spitz-box separated from said agitator chamber by vertical partition walls forming a passage connecting said chamber with said spitz-box below the froth level therein, a wall spaced from said partition wall and forming therebetween a vertical air passage opening downwardly into said spitz-box adjacent said opening, a chamber communicating with said air passage at its upper end, and a passage connecting said chamber with said agitator chamber.

Signed at Wallace, Idaho, this 21st day of May, 1925.
